UNITED STATES PATENT OFFICE

120,120

DESIGN FOR A LEAD POT HEATER

Percy M. Forster, Berkeley, Calif.

Application January 8, 1940, Serial No. 89,340

Term of patent 14 years

To all whom it may concern:

Be it known that I, Percy M. Forster, a citizen of the United States, residing at the city of Berkeley, county of Alameda, State of California, have invented a new, original, and ornamental Design for a Lead Pot Heater, of which the following is a specification, reference being had to the accompanying drawing, forming part thereof.

Fig. 1 is a perspective view of a lead pot heater embodying my new design;

Fig. 2 is a top plan view thereof;

Fig. 3 is a front elevational view; and

Fig. 4 is a side elevational view thereof.

I claim:

The ornamental design for a lead pot heater, substantially as shown.

PERCY M. FORSTER.
